Primary Examiner — Daniel Bui(74) *Attorney, Agent, or Firm* — Michael Best & Friedrich LLP(57) **CLAIM**

We claim the ornamental design for a glove, as shown and described.

DESCRIPTION

FIG. 1 is a front perspective view of a right hand glove showing our new design;

FIG. 2 is a rear elevation view thereof;

FIG. 3 is a left side elevation view thereof;

FIG. 4 is a front perspective view of a left hand glove showing our new design, which is mirroring the right hand glove of FIG. 1;

FIG. 5 is a rear elevation view thereof; and,

FIG. 6 is a right side elevation view thereof.

In the drawing views, the claimed design of a glove consists of a left hand glove and a right hand glove. The broken line represents unclaimed environments only and forms no part of the claimed design. The dash-dot line represents the boundary of the claimed design.
